Primary Examiner — Kathleen L Jones*(74) Attorney, Agent, or Firm* — J.C. Patents(57) **CLAIM**

The ornamental design for a supercomputing device, as shown and described.

DESCRIPTION

FIG. 1 is a front view of a supercomputing device; FIG. 2 is a rear view of the supercomputing device; FIG. 3 is a left view of the supercomputing device; FIG. 4 is a right view of the supercomputing device; FIG. 5 is a top view of the supercomputing device; FIG. 6 is a bottom view of the supercomputing device; FIG. 7 is a perspective view of the supercomputing device; FIGS. 8 to 17 are enlarged views of the encircled portions on FIG. 1;

FIGS. 18 to 22 are enlarged views of the encircled portions on FIG. 2;

FIGS. 23 to 29 are enlarged views of the encircled portions on FIG. 3;

FIGS. 30 to 33 are enlarged views of the encircled portions on FIG. 5;

FIGS. 34 to 41 are enlarged views of the encircled portions on FIG. 6; and,

FIGS. 42 to 55 are enlarged views of the encircled portions on FIG. 7.

The evenly spaced broken lines depicting portions of the supercomputing device form no part of the claimed design. The line-dot-line broken lines that encircle portions of FIGS. 1-7 and that border the FIGS. 8-55 detail views indicate outer limits of enlarged areas of the figures and form no part of the claimed design.
